CURRENT TRANSFORMER.

Application filed September 8, 1923. Serial No. 661,563.

Our invention relates to current transformers and more particularly to current transformers adapted for outdoor use.

One object of our invention is to provide a current transformer which is adapted for outdoor installations.

Another object of our invention is to provide a current transformer of the through type with a suitable mounting clamp which also serves as a weather-proof housing for a portion of the transformer.

A further object of our invention is to provide a current transformer for outdoor use which comprises a unitary structure.

15 In the measurement of currents traversing large capacity circuits, it has been found necessary to adopt an indirect method which frequently consists in utilizing the line conductor for the primary winding of a small 20 transformer, then measuring the current traversing the secondary winding thereof, and computing the current traversing the primary conductor. Heretofore, the use of such current transformers has been limited 25 to indoor installations. We propose to provide a current transformer of the above-indicated characteristics which is equally adapted for indoor or outdoor installations.

30 In the accompanying drawings, Figure 1 is a view, partially in elevation and partially in section, of a current transformer embodying our invention.

Fig. 2 is a plan view thereof taken along the section line II-II of Fig. 1.

35 Fig. 3 is a view, partially in elevation and partially in section, of a detail thereof.

In the several figures of the drawing, like reference numerals indicate similar parts.

40 In the preferred embodiment of our invention, a tube 1, which is preferably of copper or brass, is provided for the reception of a conductor 2 which is adapted to pass therethrough. This tube is supported by a suitable two-part clamping device 3 from 45 any suitable stationary base. The tube 1 supports a plurality of insulators 4 that are of the porcelain weather-proof type and are divided into an upper and lower group, between which is placed the clamp 3. The 50 clamp 3 terminates in a housing 5 in which is placed a core member 6 of the ring type. About the core member 6 there is wound a spiral conductor 7 which terminates in suit-

able leads 8 and 9 which extend out of the housing 5 through suitable insulating bushings 10.

The tube 1 is insulated from the several insulators 4 and the winding 7 by a bushing 11 of the condenser type. As is shown in Fig. 3, this bushing comprises a coating of insulating material 12, such as micarta, which is of uniform diameter and substantially the length of the tube 1. Within the insulating material 12 are placed a number of layers of conducting material 13 to 17, inclusive, such as tin foil. The length of these several layers decreases outwardly from the tube 1. At approximately the central portion of the bushing 11, there is placed a layer of spirally wound wire 18 which 70 serves as a binder for the bushing, as well as a point of zero potential between the clamp 3 and the tube 1.

The clamp 3 is protected from flash-overs along the outer surface of the tube 1 by 75 reason of the total surface length of the insulators 4.

In the operation of our invention, the conductor within the tube 1 is energized by the current traversing it. The core member 6 80 is thereupon energized and the conductor 7 is energized in a predetermined proportion to the energization of the conductor. The leads 8 and 9 may be carried to any remote measuring instrument or relay.

85 It will thus be seen that we have devised a current transformer for outdoor application in which the secondary winding is protected from the weather and from flash-overs. The supporting clamp for our current transformer also acts as a weather-proof housing for the secondary winding and the core member.

We do not wish to be restricted to the specific circuit connections or arrangement 95 of parts herein set forth, as various modifications thereof may be effected without departing from the spirit and scope of our invention. We desire, therefore, that only such limitations shall be imposed as are 100 indicated in the appended claims.

We claim as our invention:

1. An out-of-door current transformer comprising a metallic tube for the reception of a line conductor, a core member 105 mounted on the tube, a secondary winding

- associated with the core member and a plurality of insulators disposed on the tube between the ends thereof and the core member.
5. 2. An out-of-door current transformer comprising a metallic tube for the reception of a line conductor, a core member mounted on the tube, a secondary winding associated with the core member, a supporting and 10 housing clamp surrounding a portion of the tube and the core member, and a plurality of insulators disposed on the tube between the ends thereof and the clamp.
15. 3. The combination with a conductor, of a winding inductively related thereto, means for insulating said conductor from said winding comprising a bushing disposed therebetween, and a weather-proof housing for said insulating means and winding, said 20 housing comprising rain-deflecting structure extending longitudinally of said conductor.
25. 4. The combination with a conductor, of a winding inductively related thereto, means for insulating said conductor from said winding comprising a bushing disposed therebetween, and a weather-proof housing for said insulating means and winding, said housing comprising a series of spaced rain-deflecting structures extending longitudinally of said conductor.
35. 5. The combination with a conductor, of a winding inductively related thereto, means for insulating said conductor from said winding comprising a bushing disposed therebetween, and a weather-proof housing for said insulating means and winding, said housing comprising insulating rain-deflecting structure extending longitudinally of said conductor.
40. 6. The combination with a conductor, of a winding inductively related thereto, means for insulating said conductor from said
45. winding comprising a bushing disposed therebetween, a coil encircling said bushing adjacent said winding, and a weather-proof housing for said winding, bushing and coil.
50. 7. The combination with a housing comprising detachable members, of a transformer core and winding disposed within said housing, rain-deflecting structures extending in opposite directions from said housing, and a bushing disposed within said structures for the reception of a conductor with which said winding is inductively related.
55. 8. The combination with a housing comprising detachable members, of a transformer core and winding disposed within said housing, weather-proof structures extending in opposite directions from said housing, a bushing disposed within said structures, a coil encircling said bushing adjacent said housing, and a tube disposed within said bushing for the reception of a conductor with which said winding is inductively related.
60. 9. The combination with a housing comprising detachable members, and means for securing said housing to a supporting member, of a transformer core and winding disposed within said housing, weather-proof structures extending in opposite directions from said housing, a condenser bushing disposed within said structures, a coil encircling said bushing adjacent said housing, 70 and a tube of non-magnetic material disposed within said bushing for the reception of a conductor with which said winding is inductively related.
75. In testimony whereof, we have hereunto subscribed our names this 23rd day of August, 1923.

JESSE B. GIBBS.
GORDON A. BURR.
